UNITED STATES PATENT OFFICE.

DAVID H. ENGELSON, OF BROOKLYN, NEW YORK, ASSIGNOR TO BROOKLYN METAL STAMPING CORP., OF BROOKLYN, NEW YORK.

DESIGN FOR A RADIO VERNIER DIAL.

Application filed July 7, 1926. Serial No. 18,268. Term of patent 3½ years.

To all whom it may concern:

Be it known that I, DAVID H. ENGELSON, a citizen of the United States, residing at Brooklyn, State of New York, have invented a new, original, and ornamental Design for a Radio Vernier Dial, of which the following is a specification, reference being had to the accompanying drawing, forming a part thereof.

The figure is a perspective view of the radio dial.

I claim:

The ornamental design for a radio vernier dial, as shown.

DAVID H. ENGELSON.
